US0D1024000S

(12) **United States Design Patent** (10) **Patent No.:** **US D1,024,000 S**
(45) **Date of Patent:** **** Apr. 23, 2024**

(54) **AMPLIFIER**

(71) Applicant: **SONY GROUP CORPORATION**,
Tokyo (JP)

(72) Inventor: **Akio Suzuki**, Tokyo (JP)

(73) Assignee: **SONY GROUP CORPORATION**,
Tokyo (JP)

(**) Term: **15 Years**

(21) Appl. No.: **29/849,868**

(22) Filed: **Aug. 15, 2022**

(30) **Foreign Application Priority Data**

Feb. 17, 2022 (JP) ..... 2022-003024 D

(57) **CLAIM**

The ornamental design for an amplifier, as shown and
described.

DESCRIPTION

FIG. 1 is a front, top, right perspective view of an amplifier
showing my new design;

FIG. 2 is a rear, bottom left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrating portions of the amplifier form
no part of the claimed design.

1 Claim, 8 Drawing Sheets
